HOWARD F. BUBIER, OF LYNN, MASSACHUSETTS, ASSIGNOR TO THE SINGER MANUFACTURING COMPANY, A CORPORATION OF NEW JERSEY.

BUTTONHOLE-FLY FOR SHOES.

1,158,368.

Specification of Letters Patent. Patented Oct. 26, 1915.

Application filed March 7, 1913. Serial No. 752,547.

To all whom it may concern:

Be it known that I, HOWARD F. BUBIER, a citizen of the United States, residing at Lynn, in the county of Essex and State of Massachusetts, have invented certain new and useful Improvements in Buttonhole-Flies for Shoes, of which the following is a specification, reference being had therein to the accompanying drawings.

10 My invention relates to a buttonhole fly for shoes, and will be understood by reference to the following description taken in connection with the accompanying drawings in which—

15 Figure 1 is a view of the front or face blank with one edge skived; Fig. 2, a perspective view of a portion of the completed fly with the parts separated at one end; and Fig. 3 a transverse section, on an enlarged scale, on the plane of the line 3—3 of Fig. 2.

Similar reference numerals indicate similar parts in the several views.

My improved fly comprises a front piece 1, a back or lining 2, these two parts being preferably of leather, and an intermediate reinforcing tape 3, and is made in the following manner. The front piece is cut with a suitable templet and the edge 4 thereof skived to avoid a too great thickness along the edge when turned over. The reinforcing tape 3 is then stitched to the front piece, one edge of the tape being laid in proximity to the edge of the front piece. This work is done on a single needle machine having an attachment by which the skived edge 4 is turned under upon itself in advance of the stitching and the tape fastened down upon the turned under edge by the inner line of stitches 5. The tape serves to give the proper hold or firmness to the buttonhole. The back or lining 2 is then stitched to the front piece, over the tape, by the outer line of stitches 6, which stitches

lie beyond the outer edge of the tape. The outer edge of the back is trimmed during the stitching operation. The buttonholes 7 are then cut and stitched on any suitable machine, the buttonhole stitches serving as additional means to secure the parts of the fly together.

It has been the practice heretofore to make buttonhole flies by pasting the turned-over skived edge with rubber cement and then allowing the cement to dry before stitching the reinforcing tape. This practice has many disadvantages including the cost of the cement, the danger attendant upon its use as it is inflammable, the labor required for the work of pasting, the delay in allowing the cement to dry, and the difficulty of stitching through the cement as it sticks to the needle and fills the eye. I have done away entirely with the use of cement thus materially reducing the cost of making the fly and obviating all of the disadvantages resulting from the use of cement. Moreover, the bead formed by turning over the skived edge of the front piece presents a better appearance than when cement is used.

Having thus set forth the nature of the invention, what I claim herein is:—

As an article of manufacture a buttonhole fly for shoes comprising a front piece having one edge turned under upon itself to form a bead, a reinforcing tape overlying the turned under edge and secured to said front piece by a line of stitches, and a back piece overlying the tape and secured to the front piece by a line of stitches beyond the outer edge of the tape.

In testimony whereof, I have signed my name to this specification, in the presence of two subscribing witnesses.

HOWARD F. BUBIER.
